DITCH CLEANING AND TERRACING
MACHINE

Charles V. Stewart, Maricopa County, Ariz.

Application September 16, 1940, Serial No. 356,895

5 Claims. (Cl. 37—155)

This invention relates to a ditch cleaning and terracing machine of the type attached and drawn behind a tractor or other source of locomotion, and has for its objects,

First, to provide a machine which has two adjustable cutting blades positioned on a frame so that their angle of attack may be easily varied to accomplish the results desired;

Second, to provide such a device having frame supporting wheels attached and positioned so that it will not be easily upset or tipped over either when in use or when being drawn into or pulled out of ditches;

The third object is to provide such a machine wherein the means of support may be easily adjusted from a conveniently positioned operator's platform; said adjustment being such that the entire body of the machine may be tilted from a transverse horizontal position to an angular position, so that a ditch having an angular bottom or a V-ditch may be dug or cleaned;

A fourth object is to provide stabilizing means for the body of the device when operated in said tilted position;

A fifth object is to provide a side cutting blade supported so that it may be adjusted as to angle and cut to meet the varying conditions of the side of a ditch to be cleaned, so as to effectively clean weeds and the like from the ditch side, although the same may have a variable angle and variable width;

A sixth object is to provide, in addition to the main adjustable supporting or riding wheels, a pair of resiliently supported stabilizing wheels to maintain the lateral stability of the body;

A seventh object is to provide means of support of the front portion of the body of the device so that it may be adjusted to control the depth of cut of the blades, together with a construction which will maintain lateral stability of the front end of the device and permit the greatest latitude of adjustment of the angle of tractive effort, including a draw bar which may be swung both vertically and horizontally on hinged supports.

Other objects will appear hereinafter.

I attain the foregoing objects by means of the construction and devices illustrated in the attached drawings in which,

Figure 1 is a perspective view of the entire machine;

Figure 2 is a plan view thereof;

Figure 3 is an elevational view of the side blade showing its means of support;

Figure 4 is a fragmentary view of the lower

portion of side blade drawn on a somewhat enlarged scale showing detailed means of support;

Figure 5 is a side elevational view of the adjustable stinger wheel used to maintain lateral stability particularly when the machine is tilted to the right, as in cutting a V-ditch;

Figure 6 is a side elevational view of one of the adjustable rear support or riding wheels;

Figure 7 is an end elevation thereof;

Figure 8 is an end elevation of one of the resilient stabilizing wheels;

Figure 9 is a front cross sectional elevation of a portion of the front truck showing the rocking bolster and its construction;

Figure 10 is an outside elevational view of the manual control of the side blade.

Figure 11 is a fragmentary plan view showing details of the pin and hole latch structure controlling the position of the bottoming blade frame;

Figure 12 is a front elevational view thereof;

Figure 13 is a fragmentary plan view showing particularly the brackets supporting the stinger wheel and its adjustable support; and

Figure 14 is a fragmentary longitudinal sectional elevation of the front end of the frame showing particularly details for raising the frame from the front truck.

Similar numerals refer to similar parts in the several views.

The main frame 2 of my machine is preferably of channel or H steel, made in a V shape with the point of the V at the forward end. The two side members, 3 and 4, of the frame are joined at

35 the front end by a web block 5, and at the rear by cross members 6 and 7 and by an X brace 8 at approximately their middle. The rear of each of these side members is bent downward, and at the ends there are knuckle joints 9 affording support for the forks 10 of the rear supporting and riding wheels 11. The front of the machine is supported on a two wheeled truck 12 having a fifth wheel 13 of the turntable type surmounted by a rocking bolster 14. This is, in turn, connected to

40 the frame by two upright supporting rods 15 extending vertically through the front frame web. These upright rods are joined at the top by a cross bar or yoke 16, to which they are welded.

Yoke bar 16 is provided with bearing lugs 160 welded to about the middle of its top face (see Figure 14).

45 A longitudinally extending hand lever 17 is pivoted in the prow 18 which extends upward from the front end of the frame. This lever is provided with a hand latch operating with a ratchet

19. A link 20 is connected to the yoke 16. A link 20 operatively joining the hand lever 17 and the yoke bar 16 is connected at the top to the hand lever by a cross pin bearing and to the yoke 16 at its bottom by the bearing bolt 161. By this arrangement the front end of the frame may be raised or lowered relative to the front truck. The forks 10 of the riding wheels are each individually adjustable by means of hand levers 22 pivotally mounted on the rear end of the frame pieces at 25 and connected by links 26 to lugs 27 on the forks 10. Levers 22 are provided with hand latches 28 which operate on toothed latch segments 29 so that the forks supporting the wheels may be maintained in any desired angle relative to the knuckle joint 9. This provides a means for adjusting the height of the rear of the frame from the ground. Since each riding wheel is made independently adjustable, the transverse plane of the rear portion of the frame may be 20 varied relative to the level of the ground on which the riding wheels rest.

As viewed assembled, this device consists of the frame and its supporting members, above described, on which are carried two blades. One of these blades is termed the bottoming blade, indicated by numeral 30. This is supported about two-thirds of the length of the frame from its front, on a pivotally mounted blade holder, generally indicated by numeral 31. The other is a side cutting blade 32 extending from the right hand side of the frame. Its lower end is supported in a ball and socket joint 33 attached to the lower tip of a downwardly curved horn support 34. The rear portion of this blade is supported vertically by a ball and socket joint 35 at the lower end of an adjustable double piece link 36, which is, in turn, connected by a ball and socket joint 37 to a crank 38, operative on a sector gear 39 contained within a housing and mounting 40 and driven by a worm 41 on a shaft operated by a hand wheel 42.

In approximately the middle of blade 32 an adjustable two piece compression link 43 is attached to the blade by means of a clevis 44 and to the side member 4 of the frame by eye link 45. The vertical or cutting position of the blade is maintained by an eye bolt 46 engaging a rod 47 on the upper edge of the blade attached to a lug 48 on the inner edge of the downwardly extending portion of the horn support 34. This horn support is attached to the right hand frame member 4 by a pivot bolt 50 at its front end, and a buckhead 51, having a number of arcuately positioned attachment holes 52 to receive attachment bolt 53 and provide for vertical adjustment of horn 34 relative to the frame. The horn support 34 is bent downward and outward from buckhead 51 to the point of attachment of the front end of the blade, as above described.

Above the rear portion of the frame, a control platform and frame 60 is erected on vertical supports 61. The lower ends of these supports are attached to the rear of the frame members 3 and 4. At the right end of this platform frame the housing 40 which contains the worm and sector gears 41 and 39, is mounted. This housing is provided with suitable braces to render it rigid. It will be noted that frame 60 is erected above the main frame 2 so that the control of the rear end of blade 32 is above the point of control, i. e. the ball and socket joint 35. To the rear of this frame two braces 63 extend diagonally rearward to afford support for the riding platform 64, which extends horizontally outward from the

5 rear end of the frame. It will be noted that the riding wheel control levers 22 are within easy reach of an operator standing on this platform, also that the hand wheel 42 is likewise conveniently disposed. Further, the front elevating lever 17 is immediately in front of this platform.

10 Attached beneath the rear downward bend of the frame members 3 and 4 and at each side of the body of the frame are sleeves 68, the axis of which is transverse relative to frame 2. These sleeves are welded to the frame members and to the cross member 6 and to a vertically extending support member 69 which affords end support for the cross piece 7. These sleeves journal shafts 10, the outer ends of which are turned downward forming knees 71. At the lower ends of these knees, stabilizing wheels 72 are supported on outwardly extending axles 73. Extending above each shaft 10 and near the outer ends there are cranks 74. To these cranks the forward end of long coiled springs 75 are attached by links 76. The rear ends of these springs are attached to a cross member 77 attached to the rear of the platform 64. The tension of these springs maintains the knees 71 in a substantially vertical position. Ordinarily this tension is such that the knees extend only slightly to the rear of a vertical position.

25 At the upper ends of levers 74, chains 78 are attached and joined at a convenient point on the frame. These chains limit the pull of springs 75 and prevent them from pulling the knees beyond a vertical position.

30 In Figure 8, it will be noted that the stabilizing wheels extend laterally beyond the riding wheels. The line of their track may be adjusted by providing longer shafts 70 within sleeves 68. However, for all ordinary uses their lateral position may be fixed and, it is to be understood, that in use, while the riding wheels roll in the bottom of the ditch being cleaned, these stabilizing wheels ride on the sides of the ditch and thus afford adequate lateral stability while at the same time conforming to the irregularities to the sides 35 of the ditch being cleaned.

35 Referring now to the bottoming blade 30, it will be noted that the lower or compression member 79 of the blade support 31 is pivoted at 184 to a cross frame member 80. An upper frame support member 81 pivotally slides freely on top of the main frame members 3 and 4. The angular position of this blade is adjustably maintained by a pin and hole latching mechanism. This consists of a vertically positioned pin 84 supported in a guide 180. This pin is provided with a slotted hole 181 to receive the forward end of the handle bar 82, which fulcrums and is supported by bearing lug 182 on cross frame member 80 (see Figure 11). Pin 84 is normally urged downward and toward engagement with any one of a plurality of holes 83 in sector plate 183 formed on lower compression member 79 of the bottoming blade support 31 by a spring 185 surrounding it. When the rear end of handle bar 82 is depressed pin 84 is lifted clear of engagement with sector plate 183 and the member 79 is free to swing horizontally on its bearing bolt 184.

40 Referring to the front truck 12, it will be noted that the two wheels 85 are supported on individual axles fastened to a yoke shaped framework 86 which is, in turn, hingedly connected by knuckle joints 87 to the turn table type fifth wheel 13 (see Figure 9). The stationary portion of this fifth wheel indicated by 89, is made in the shape of a pan having comparatively steep sides,

the forward and rear ends of the shaft 90 of the rocking bolster 14 are fitted into bearings in the front and rear sides of this pan shaped body. The draw bar 91 is pivotally attached to a cross member 92 extending between the sides of the yoke 86. The forward portion of this yoke is provided with a plurality of holes 93 through which a pin 94 may be dropped to engage the draw bar 91 in any desired draft angle.

In use it is often desirable to tilt the entire framework of the machine somewhat sharply to the right. In order to afford additional support when so used, I provide a stinger wheel 100, which is adjustably supported at the right hand edge of the frame, extending outward therefrom a slight distance beyond the right hand resilient stabilizing wheel. Support for this wheel is afforded by a bracket 101 welded to the right hand upright side plate 69, extending outward the required distance and welded to a housing 102, in which there are three parallel substantially vertically extending holes. The outer holes afford a sliding support for bars 103 and 104 which slide freely therein.

The lower end of these bars is attached to a block 105 in which the stinger wheel axle 106 is set. The center hole accommodates a long screw 108 to which a hand wheel 109 is attached at the top and a follower block 110 at the bottom. A threaded boxing 111 is attached to the housing 102 to accommodate the threads on the rod 108. When hand wheel 109 is rotated therefore, the wheel supporting block 105 is raised or lowered. Hand wheel 109 is conveniently positioned relative to the platform 64 at the right hand side of the body and just below the side blade operating hand wheel 42. Since the right hand stabilizing wheel 72 may carry more load than the left hand stabilizing wheel, a second spring 117 may be attached parallel to the right hand stabilizing wheel spring 75. The left end of this spring is shown broken away in Figure 2 so as not to obscure parts beneath it.

In operation the draw bar 91 is attached to a convenient tractive means such as a caterpillar or wheel tractor and conveyed to the work with the supporting wheels in extended downward position as indicated in Figure 1, and the front end of the frame raised as shown in this figure. Where the work desired is cleaning a flat bottomed ditch with slanting sides, the machine is set up as illustrated in both Figures 1 and 2. Preferably the tractor should be of a size that will run in the bottom of the ditch, although the adjustability of the draw bar as to the front truck will accommodate a tractor running on the side of the ditch. The front end of the frame is lowered by raising lever 17 until the bottoming blade 30 engages soil to the proper depth of cut desired in the bottom of the ditch. Riding wheels 11 are adjusted accordingly and individual adjustments are made to accommodate any slant in the ditch bottom. Side blade 32 is adjusted so that its forward edge or cutting point 120 is approximately even with the bottom or cutting edge of the bottoming blade 30. It is then positioned so that it has an outward and upward angle. This angle is adjusted for the particular job usually by the compression bar 43. Manipulation of the hand wheel 42, however, will raise and lower the vertical position of this blade as it turns on its forward ball and socket support 33, and, due to its angular position, the blade may be thus adjusted both as to the width and angle of the side of the ditch. Thus the blade 75

may be lowered when the angle drops off or when the ditch widens slightly. Since in cleaning ditches it is necessary that this blade follow the contour of the ditch side in order to clean and cut out grass roots, weeds, and other undesirable vegetation, it is necessary as the machine is drawn forward to make this side blade follow the contour of the face of the ditch side by a manipulation of this wheel 42. Of course, if a ditch is ideally constructed and the side being cleaned is smooth and of uniform angle, this would not be necessary. In practice, however, the contrary is true. After the machine has been drawn through the ditch in one direction and has cleaned the bottom and one side, it will be noted that the bottoming blade has forced soil and substances encountered in the bottom of the ditch to the left. The machine is then turned around and drawn through the ditch in the opposite direction and the side blade engages the ridge of soil previously left by the bottoming blade on the left hand side of the ditch during the first operation. In this manner, flat bottom ditches are efficiently cleaned.

Where the machine is used to clean V shaped ditches, then the right hand riding wheel is moved to its lowered position and the left hand wheel is raised. This tilts the frame 2 to the right. The principal weight of the machine then rides on the right hand riding wheel, the right hand stabilizing wheel, and the stinger wheel 100, which is adjusted to roll on the right hand side of the ditch. When so adjusted the bottoming blade 30 engages the left hand side of the V shaped ditch and the side blade 32 engages the right hand edge. Hand wheel 42 is manipulated to secure this adjustment. Obviously the position of blade 32 may be quickly adjusted to accommodate this type of work, if necessary, by changing the supporting bolts in the buckhead 51 and also by changing the main angle of the blade by adjustment of the double piece compression link 43.

In the same manner as last described V ditches may be dug in level soil. Where the device is used for terracing and contouring, then the side blade 32 may be dispensed with and only the bottoming blade used. However, even in this operation the side blade may be used to even the inner cut on the high side of the terrace level and may be adjusted accordingly.

In all operations, the stabilizing wheels 72 afford a resilient means of support for the frame and body structure of the entire machine and prevent accidental upset. Added to this novel feature is the fact that I have provided a two-wheel front truck. Ordinarily this truck runs in the bottom of the ditch being cleaned, and tilts sideways according to its lateral slant. In moving the machine into and out of ditches, I have found that it is necessary to permit the front truck to follow the contour of the ground on which it is rolling independently of the lateral slant of the ground on which the rear portion of the machine is rolling. Thus when the frame is in the raised position as shown in Figure 1, the rocking bolster permits the frame to swing freely on a longitudinal axis relative to the front truck. This is very necessary in preventing upsets and provides a flexible means for supporting the front end of the device. When the frame is in fully lowered position then a cross bar 118 attached to the front end of the frame rests on each side of the rocking bolster pan 89 and in this position the frame is urged to follow the

lateral slant of the truck. This is necessary for properly following the lateral slant variance in the bottom of any ditch being cleaned.

I claim:

1. A combination ditch cleaning and terracing machine, comprising, in combination, a frame having a centrally positioned pivotally mounted bottoming blade thereon and a side cutting blade adjustably mounted on one side thereof, wheeled support for said frame including a truck at the forward end thereof having a rocking bolster intermediate said truck and said frame and means for manually raising or lowering said frame on said truck, and riding wheels mounted on the rear of said frame each manually adjustable to vary the height of the frame from the ground on which said riding wheel rests, and lateral stabilizing means including resiliently supported stabilizing wheels extending laterally on each side of said frame and bearing on the ground at lateral positions beyond the track of said riding wheels.

2. The combination ditch cleaning and terracing machine including in combination, a frame having a centrally positioned pivotally mounted bottoming blade mounted thereon, a side cutting blade adjustably mounted on one side thereof, said adjustable mounting including an adjustably positioned ball and socket joint attached to the forward end of said blade and a variable rear mounting having means for manual adjustment of the vertical angle of said blade, a wheeled support for said frame including a draw truck at the forward end provided with an adjustable draw bar, a fifth wheel, a rocking bolster and means of attachment to the forward end of said frame whereby the height thereof may be manually adjusted relative to said draw truck, and riding wheels hingedly mounted on the rear of said frame, each individually manually adjustable to vary the height of the frame relative to the ground on which said wheel rests, and lateral stabilizing means including stabilizing wheels resiliently supported on shafts extending transversely of said frame whereby said wheels engage the earth to track beyond the tracks of each of said riding wheels.

3. A ditch cleaning machine including in combination, a frame having a general triangular shape with an operator's platform attached at the rear thereof, a bottoming blade pivotally mounted at approximately the center thereof and means for latching said blade in any desired pivotal position, a side cutting blade rigidly and adjustably mounted at the forward end thereof to one side of said frame, means for supporting the rear end thereof manually adjustable so that the horizontal angle of said side cutting blade may be manually adjusted, together with an adjustable compression link extending from approximately the center of said blade to the side of said frame, together with wheel means for supporting said frame including a two wheel draw truck at the forward end provided with a draw bar having means for horizontal and vertical adjustment, a fifth wheel and a rocking bolster thereabove having means of attachment to the forward end of said frame to provide for raising and lowering the frame relative to said truck, individually mounted riding wheels attached to each side of the rear of said frame by forks and knuckle joints, each having latch and lever mechanism to provide for raising and lowering the frame relative to the ground on which said wheel

rests, stabilizing means including resiliently supported stabilizing wheels positioned to track laterally beyond the track of said riding wheels and an auxiliary supporting wheel adjustably mounted on the side of the frame which supports the side cutting blade.

4. A ditch cleaning machine, including, in combination, a triangular shaped frame having two side members joined by a web at their forward end and bent downwardly at their rear ends terminating in knuckle joints, riding wheels supported in forks attached to said knuckle joints, levers attached to said frame and connected to said forks, having latching means whereby said riding wheels may be independently raised or lowered relative to their point of attachment on said frame, an operator's riding platform attached to and extending from the rear of said frame between said riding wheel adjusting levers, a platform attached to and extending upward from the rear of said frame, a side cutting blade attached to one side of said frame and being rigidly and adjustably mounted at its forward end by a downwardly extending horn having a socket joint at its lower end to receive a ball support on the forward end of said blade, and a buckhead at substantially its middle to provide vertical adjustment of said horn relative to said frame, an adjustable compression link extending outward from said frame to approximately the middle of said blade, and means for adjustably supporting the rear portion of said blade including a ball and socket joint on the rear portion thereof connecting to an adjustable link supported on a crank operated through intermediate gearing by a hand wheel supported on said vertical platform above said frame, an auxiliary riding wheel positioned between said side cutting blade and the frame adjacent thereto, including a stinger wheel rigidly mounted on a substantially vertically adjustable block, the vertical position thereof being controlled by a hand wheel positioned within easy reach of an operator on said riding platform, and a support for the forward end of said frame including a truck having a vertically and horizontally adjustable draw bar and means for attachment of said truck to the forward end of said frame, including a fifth wheel, a rocking bolster and upwardly extending rods joined by a yoke connected by a link to a lever positioned on the forward end of said frame whereby said frame may be raised and lowered relative to said truck and stabilizing wheels mounted on knees extending downwardly from lateral shafts turning in sleeves mounted on each side of said frame, said shafts having upwardly extending levers with long springs attached thereto and to the rear end of said riding platform whereby said knees are normally urged downward, chains forming a limiting means to prevent said knees from moving beyond a predetermined vertical position, said shaft supporting said knees, being proportioned so that said stabilizing wheels extend beyond the tracks of said riding wheels.

5. In a machine for cleaning ditches having a frame including side members, a side blade supporting means including, in combination, a front support having a bar parallel to said frame at its forward end and a downwardly extending horn at its rearward end, a pivotal bolt extending through the forward end of said bar in said frame and a buckhead formed on the rear portion of said bar provided with a plurality of holes to permit vertical adjustment of the tip of said horn

support relative to said frame member, a ball and socket joint joining the forward end of said blade with the tip of said horn support, an eye bolt extending between the upper edge of said blade and a lug positioned on said horn above the tip thereof to maintain said blade in cutting position, lateral supporting means for said blade including an adjustable link extending from a clevis on said blade to an eye link on said frame,

5 and means for adjustably supporting the rear end of said blade including an adjustable link connected to the rear end of said blade by a ball and socket joint at its lower end and to a crank at its upper end, together with means for operating said crank including worm and sector gears and an operative hand wheel.

CHARLES V. STEWART.
